US00D976100S

(12) **United States Design Patent** (10) **Patent No.:** **US D976,100 S**
Sill et al. (45) **Date of Patent:** **** Jan. 24, 2023**

(54) **CLOSEABLE CONTAINER**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/764,305**

(22) Filed: **Dec. 29, 2020**

Related U.S. Application Data

(62) Division of application No. 29/700,669, filed on Aug. 5, 2019, now Pat. No. Des. 906,100, which is a division of application No. 29/615,120, filed on Aug. 25, 2017, now Pat. No. Des. 879,603, which is a division of application No. 29/573,602, filed on Aug. 8, 2016, now Pat. No. Des. 799,317, which is a division of application No. 29/545,314, filed on Nov. 11, 2015, now Pat. No. Des. 776,522.

(57) **CLAIM**

The ornamental design for a closeable container, as shown and described.

DESCRIPTION

FIG. 1 is a perspective view of a closeable container showing our new design;

FIG. 2 is a front elevation view thereof, the rear being a mirror image;

FIG. 3 is a right side elevation view thereof, the left side being a mirror image;

FIG. 4 is a top plan view thereof;

FIG. 5 is a bottom plan view thereof;

FIG. 6 is a plan view of the closeable container showing the closeable container in a blank configuration; and,

FIG. 7 is another perspective view of the closeable container showing the closeable container in an open configuration. In the Figures, the dash-dash broken lines are for the purpose of illustrating perforations.

1 Claim, 6 Drawing Sheets
